Primary Examiner — L. A. Grabenstetter(74) *Attorney, Agent, or Firm* — Howard & Howard Attorneys PLLC(57) **CLAIM**

The ornamental design for a self-aligning surgical drill bit, as shown and described.

DESCRIPTION

FIG. 1 is a top, proximal left perspective view of a self-aligning surgical drill bit;

FIG. 2 is a bottom, proximal left perspective view thereof;

FIG. 3 is a top, distal right perspective view thereof;

FIG. 4 is a bottom, distal right perspective view thereof;

FIG. 5 is a proximal end view thereof;

FIG. 6 is a top plan view thereof; and,

FIG. 7 is a left side elevational view thereof.

In the drawings, the broken lines illustrating the self-aligning surgical drill bit form no part of the claimed design. The self-aligning surgical drill bit is shown with symbolic breaks in its length. The appearance of any portion of the article between the break lines forms no part of the claimed design.
